UNITED STATES PATENT OFFICE.

RICHARD C. ROSE, OF OSCEOLA, ARKANSAS.

WATCHMAN'S CLOCK.

971,309.

Specification of Letters Patent. Patented Sept. 27, 1910.

Application filed March 10, 1910. Serial No. 548,355.

To all whom it may concern:

Be it known that I, RICHARD C. ROSE, a citizen of the United States, residing at Osceola, in the county of Mississippi and State 5 of Arkansas, have invented a new and useful Watchman's Clock, (Case A,) of which the following is a specification.

This invention has reference to improvements in watchman's clocks and its object is 10 to provide a clock system wherein the clock will automatically set itself into position to give an alarm if the watchman fails to properly operate means at a predetermined distant station.

15 The invention will be best understood from a consideration of the following detail description taken in connection with the accompanying drawings forming a part of this specification, in which drawings:—

20 Figure 1 is a diagram illustrating a watchman's clock with the invention applied. Fig. 2 is a detail section through one of the armature mountings used in connection with the structure of Fig. 1.

25 Referring to the drawings there is shown a clock 1 which may be installed at any suitable point in the system and so far as the time side of the clock is concerned it may be of any approved type. The clock carries a 30 hand or arm 2 which may be one of the time indicating hands of the clock or may be a separate arm not visible to the casual observer. In the path of the hand or arm 2 are contact fingers 3, in number depending 35 on the distance traversed by the hand or arm in a given time, and the time intervals at the ends of which the watchman is expected to cause the proper operation of the clock. The fingers 3 may be spring fingers 40 and the hand or arm 2 may be arranged to sweep across these fingers so as to make contact therewith, and by properly arranging the parts this contact may be quite short in duration and sufficiently light to constitute 45 no impediment to the operation of the clock but at the same time give good electrical contact.

At appropriate points adjacent to the clock 1 are mounted levers 4 preferably 50 upon a centrally located pivot post 5 which may be threaded to receive a clamp nut 6 so that each lever 4 may move under the application of an appropriate force but will maintain the position to which it is moved 55 by the friction caused by the engagement therewith of the clamp nut 6. The same

stem or post 5 may receive a thumb nut 7 constituting the movable member of a binding post for attaching a conductor to the stem or post 5, or a conductor may be soldered or otherwise connected to the lever 4. On the lever 4 are armatures 8, 9 in operative relation to which are electro-magnets 10, 11 respectively. These two magnets 10, 11 may constitute the two members of an ordinary horseshoe electro-magnet, or they may be separate electromagnets. Each lever 4 carries two contact brushes 12, 13 at the respective ends. The lever 4 is a polarized lever so that it will move toward 70 the pole piece of one or the other of the magnets 10 or 11 in accordance with the direction of flow of current through these magnets and the polarity of their pole pieces. The brushes 12 and 13 are so disposed that when the lever 4 is rocked in one direction the brush 12 is in the path of the arm or hand 2 and when the lever is rocked in the other direction the brush 13 is in the path of the arm or hand 2 and when one 80 brush is in the path of said hand the other brush is out of the path of said hand. There is a contact 3 in the path of the hand 2 in advance of both brushes 12 and 13 upon the lever 4.

85 The magnet 10 is connected on one side to a conductor 14 including a battery 15 or other source of electric energy and this conductor leads to some distant point where its continuity is broken by a key or push button 16 from whence the conductor may lead to ground as indicated at 17 or may be brought back to another conductor 18 leading to one side of the magnet 11. The conductor 18 is however in the drawings indicated as grounded at 19. The two magnets 10 and 11 are coupled together by a conductor 20 so that when the circuit is closed at the circuit controller 16 there is established a circuit from the battery 15 by way 90 of the conductor 14 to the circuit controller 16 thence to ground at 17, returning by ground at 19 through the conductor 18 and traversing the two magnets 11 and 10 and finally again reaching the battery 15, the 105 assumption being that the circuit is completed by closing the circuit controller 16. The conductor 14 between the magnet 10 and the battery 15 is connected by a branch conductor 21 to the contact finger 3, or to 110 the contact fingers 3 if there be more than one of them.

The hand or arm 2 is connected by a conductor 22 to the conductor 18 and includes a battery 23 or other suitable source of electric energy. The lever 4 is connected by a conductor 24 through a battery 25 to one side of a bell 26 or other suitable signal device and the other side of this bell 26 is coupled by a conductor 27 to the conductor 22.

There may be as many contact fingers 3, 10 levers 4 and magnets 10, 11 as may be desired, and these devices will be disposed around the clock so as to be engaged by the hand or arm 2 in any order adapted for the purposes of the invention. Each magnet 10 15 is coupled by a conductor 14 to a battery 15 and ultimately to a key or circuit controller 16.

Let it be assumed that the hand 2 is moving under the action of the clock movement, 20 then at a certain time it will engage a spring contact 3 and there will be established a circuit from the battery 23 to the conductor 22, to the hand 2, thence by the spring finger 3 engaged thereby to conductor 21, thence by 25 the conductor 21 through the magnet 10 and from the latter to the magnet 11 and ultimately back to the battery 23. Current will flow through the magnets 10 and 11 in a certain direction so as to produce a polarity in 30 the pole pieces of the two magnets such as will cause an attraction of one end of the lever 4 and the repulsion of the other end in a manner to rock the lever on its central pivotal support 5, thereby withdrawing the 35 contact finger 12 from out the path of the hand or arm 2 and moving the contact finger 13 into the path of this arm or hand 2. If now it be assumed that at the proper time the watchman arrives at the predetermined 40 station and there depresses the key 16 or otherwise closes the circuit, if the structure be another type of circuit closer than a key, then there is established a circuit from the battery 15 through the conductor 14 to the 45 ground 17, thence by the ground 19 to the conductor 18 and through the magnets 11 and 10 to the battery 15. The battery 15 is so coupled in the circuit that the current traversing the magnets 11 and 10 is the 50 reverse of that traversing the magnets from the battery 23 with the result that the polarity of these magnets is reversed, and the lever 4 being a polarized lever, its position is reversed, the end formerly attracted now 55 being repelled, and the end formerly repelled now being attracted so that the brush 12 is moved into the path of the hand or arm 2, while the brush 13 is moved out of the path of the hand or arm 2. But the 60 proper time for the watchman to manipulate the circuit controller 16 is so related to the movement of the hand 2 that it has already moved by the contact finger 12 and is approaching the contact finger 13. Since 65 however the finger 13 is no longer in the

path of the hand or arm 2, the latter continues its movement without engaging either finger 12 or 13 and is electrically inactive until it again moves into engagement with the finger 3 first considered or with another finger 3 in its path. If it be considered that the hand again reaches the first named finger 3, then the magnets 10 and 11 are energized as first described and the lever 4 is rocked so as to move the finger 12 out of 75 the path of the oncoming hand or arm 2 and moves the finger 13 into the path of the said arm or hand 2. If however the watchman fails in his duty, then the finger 13 still remains in the path of the onmoving hand 80 or arm 2 and is ultimately engaged thereby thus establishing a circuit from the battery 25 through the bell 26 thence by way of the conductors 27 and 22 to the hand 2, thence by the finger 13 to the lever 4, and back to 85 the battery by the conductor 24. This will cause a signal on the bell 26, or if the bell be replaced by some other electrically operated mechanism the latter will be actuated. Whenever the hand or arm reaches a finger 90 3, the magnets 10, 11 are energized and the adjacent finger 12 is moved out of the path of the arm 2 while the finger 13 is moved into the path of this arm and unless the circuit controller 16 be actuated within the time 95 limit determined by the movement of the hand or arm 2 from a point between the fingers 12 and 13 to the finger 13, then a signal will be caused. The space between the fingers 12 and 13 may be so regulated 100 that the watchman has only a comparatively small margin of time within which to manipulate the circuit controller 16 to cause the finger 13 to move out of the path of the arm or hand 2. If the circuit at the circuit 105 controller 16 is closed too soon then the hand or arm 2 will engage the finger 12 and a signal will be caused. If the circuit controller 16 is manipulated too late then the hand or arm 2 will engage the finger 13 and 110 a signal will be caused.

By the employment of a suitable number of magnets, 10, 11 and levers 4 with the fingers 12, 13, and the contact fingers 3 the watchman may be compelled to cover the 115 territory to be protected within a predetermined time under the penalty of having a signal caused should he fail to reach the several stations in time and in the proper order.

The signal device 26 is located at some point, say the superintendent's office if the installation be in a factory, and the clock may be also located in the superintendent's office.

What is claimed is:—

1. In a watchman's clock, a contact hand or arm having a progressive movement, a contact constantly in the path of said hand or arm, a polarized armature lever inter- 130

mediately pivoted, contacts on said armature lever and either of them movable by the rocking of the lever into path of the hand or arm, electro-magnets, one controlling 5 one end of the armature lever and the other controlling the other end of said armature lever, a charged signal circuit connected to the hand and to the armature lever, a charged circuit including the hand, the magnets, and the 10 magnets, and the contact constantly in the path of said arm, and a charged circuit including the magnets and a circuit controller and adapted to energize the magnets reversely to the circuit including the magnets, hand and 15 contact constantly in the path of the latter.

2. In a watchman's clock, a contact hand or arm having a progressive movement, a contact constantly in the path of said hand or arm, a polarized armature lever immediately 20 pivoted, means for maintaining the lever in actuated positions about its pivot support, contacts on said armature lever, and either of them movable by the rocking of the lever into the path of the hand or 25 arm, electro-magnets one controlling one end of the armature lever and the other controlling the other end of said armature lever, a

charged signal circuit connected to the hand and to the armature lever, a charged circuit including the hand, the magnets and the 30 contact constantly in the path of said arm, and a charged circuit including the magnets and a circuit controller and adapted to energize the magnets reversely to the circuit including the magnets, the hand, and the contact constantly in the path of the latter. 35

3. In a watchman's clock, a progressively movable contact hand or arm, other contacts movable into and out of the path of the hand or arm, a polarized armature lever carrying 40 said contacts, electro-magnets for causing the movement of the armature lever, means controlled by the hand or arm for causing the energizing of the electro-magnets in one direction, and manually controllable means 45 for causing the energizing of the magnets in the other direction.

In testimony that I claim the foregoing as my own, I have hereto affixed my signature in the presence of two witnesses.
